UNITED STATES PATENT OFFICE

100,302

DESIGN FOR A COMBINED MERCHANT- DISE DISPLAY STAND AND ORDER- ING COUNTER

Charles H. Thorstensen, Ogden, Utah, assignor
to Rotary Patented Displays, Inc., Ogden,
Utah, a corporation of Utah

Application March 3, 1936, Serial No. 61,461

Term of patent 7 years

To all whom it may concern:

Be it known that I, Charles H. Thorstensen, a citizen of the United States, residing at Ogden, in the county of Weber and State of Utah, have invented a new, original, and ornamental Design for a Combined Merchandise Display Stand and Ordering Counter, of which the following is a specification, reference being had to the accompanying drawing, forming part thereof.

Figure 1 is a perspective view, and
Figure 2 is a top plan view of a combined merchandise display stand and ordering counter showing my new design.

I claim:

The ornamental design for a combined merchandise display stand and ordering counter, as shown.

CHARLES H. THORSTENSEN.
